CARD INDEX

John B. Hitchings, Long Beach, Calif.

Application October 8, 1948, Serial No. 53,408

5 Claims. (Cl. 40—102)

1

My invention relates to an indexing device, and more particularly to a card index adapted to be removably affixed to the sun shield which is normally provided in an automobile.

Although numerous card indexes have been devised and marketed in the past, the majority of these devices are not adapted for the need of salesmen who travel from place to place by automobile. The conventional card index includes a container for holding the cards in a predetermined position, with the container adapted to be situated in a stationary position. Thus, it will be apparent that a salesman requiring a card index which can be used when driving an automobile cannot satisfactorily use any one of the presently available indexes as they are not designed to remain in an upright position on the sloping seat of an automobile. In addition, there is the constant danger that the cards will be blown from or displaced in the container by the wind which is normally present when an automobile is in motion. It is to eliminate the disadvantages of the prior card holding devices that I have devised my present card index which is adapted to be removably positioned on the sun shield of an automobile, and when so positioned maintain a number of cards in the desired relationship with one another.

A major object of my invention is to provide a card index which can be removably affixed to the sun shield normally provided in an automobile, that will permit the easy removal or insertion of one or more cards, can be easily affixed to and removed from the sun shield of an automobile, and due to its ease of operation the index can be used by the driver of a vehicle during the time the vehicle is in motion.

Another object of my invention is to provide a card index having an extremely simple mechanical structure, that can be manufactured from standard commercially available materials, that will be easy to fabricate, and due to its ease of manufacture can be sold at a sufficiently low cost as to encourage its wide spread use by individuals having need for such a piece of equipment.

These and other objects and advantages of my invention will become apparent from the following description of a preferred form thereof, and from the drawing illustrating that form in which:

Fig. 1 is a front elevational view of my card index removably affixed to the sun shield of an automobile which is indicated in phantom line;

Fig. 2 is a fragmentary perspective view of a portion of the device taken on the line 2—2 of Fig. 1;

2

Fig. 3 is a perspective view of two of the card holding members engaging the supporting rod; and

Fig. 4 is a perspective view of one of the clamps used in removably mounting the card index supporting bar on a sun shield of a vehicle.

Referring now to Fig. 1 for the general arrangement of my invention it will be seen that a number of cards supporting frames F are movably mounted on a horizontally positioned bar B, with the bar being removably affixed to the sun shield S of a vehicle by two clamps C, one of which is affixed to each end of the bar B.

Each of the clamps C as may best be seen in Fig. 4 includes a vertically positioned U-shaped member 10 having two laterally spaced arms 11 and 12 respectively, which embrace the sides of the sun shield S as may best be seen in Fig. 1. Extending outwardly from the exterior side of the leg 11 is a tubular L-shaped member 13 having an extremity 13a which extends inwardly and is in alignment with the similar extremity of the clamp C situated on the opposite end of the sun shield S. Each of the clamp portions 13a is substantially straight and is formed with a longitudinally extending bore 14 that is preferably tapped.

In Fig. 1 it will be noted that the bar B is made up of two members 15 and 16 of circular cross section, each of which is provided on its outer end with threads adapted to engage the tapped bore 14 of one of the clamps C, and hold the member in a non-rotating position. The inner end of each of the members 15 and 16 is provided with threads 17 and 18 respectively, with the threads being formed in opposite directions. A cylindrical handle 19 is centrally positioned on my device and is formed with a longitudinally extending bore, with each end of the bore being tapped to engage one of the threads 17 and 18. It will be apparent that the handle 19 may take any desired shape which is convenient to rotate, with such rotation causing the threaded portions 17 and 18 to be moved in opposite directions whereby the clamps C are caused to engage or be disengaged from the vertical edges of the sun shield S. Should it be desired a number of indentations 21 can be formed in the external surface of the handle 19 to facilitate its rotation when my device is being affixed to or removed from the sun shield S.

In Figs. 2 and 3 it will be noted that each of the members 15 and 16 has a number of spaced longitudinally extending grooves 22 formed on the exterior surface thereof which are engaged by a portion of the frames F as will hereinafter be explained. Although the members 15 and 16

can be formed from any rigid material I prefer to use wood or plastic for this purpose due to its lightness, and the attractive finish which may be placed thereon.

Each of the frames F as may best be seen in Fig. 1 is used in holding one or more cards of a particular class, with the result that the cards may be arranged either alphabetically or numerically as the work of the salesman or the person using my device may require. The structure of each of the frames F includes a substantially horizontally positioned cross piece 24 having a downwardly extending leg 25 appended to each end thereof. Each of the legs 25 include a downwardly extending member 26 which has the lower portion thereof doubled back to form a compressed, inverted, U-shaped member 27 the outer leg of which terminates at the bottom in an annular ring 28. Formed on the extremity of the ring portion 28 is an indented portion 29 which serves to engage one of the grooves 22 as the frame F is rotated into the desired position. The material forming the frames F must have sufficient rigidity to hold the cards in the desired position, but at the same time must have sufficient resiliency to grip the cards and the member 15 or 16 on which it is movably supported.

In Fig. 1 it will be noted that a number of the frames F are positioned on both the members 15 and 16, with the rings 25 of one frame F being adjacent to the rings of the frame F situated directly in front thereof. Thus, any one of the frames F can be easily removed from the supporting bar B, as well as additional frames supported on it when the occasion so requires.

The operation of my invention is extremely simple. Upon it being desired to use the device in a vehicle, the sun shield S is rotated downwardly into a substantially vertical position. The handle 19 is rotated until the members 15 and 16 have been moved outwardly sufficiently so that the side walls of the sun shield 20 can be engaged between the arms 11 and 12 of each clamp C. The handle 19 is now rotated in the opposite direction with the result that the clamps C are moved together, and my device is held in position on the sun shield S due to the engaging action of the clamp C.

Index cards 30 of a conventional nature are now slidably inserted in the frames F to be gripped between the members 26 and the inner legs of the U-shaped members 27. Due to the resilient construction of the legs 25 the cards 30 are firmly but removably held in position therein. Each of the cards 30 preferably has a tab extending outwardly therefrom on which is printed a number or letter as may be seen in Fig. 1 for quickly locating the desired card. For instance, should it be desired to obtain information listed on the card C, the operator of the vehicle simply reaches up and grasps the tabs having A and B marked thereon and rotates them downwardly sufficiently so that the information on the card C can be easily read. The cards A and B upon being rotated downwardly will remain in this position due to the indented portions 29 on the rings 28 engaging one of the grooves 22 as may best be seen in Fig. 2. Although the indented portions 29 are pressed inwardly with sufficient force to hold a particular frame F in the desired position, the indented portions are easily moved from the groove 22 they are engaging by but a slight amount of force being applied to the frame F.

In Fig. 1 it will be seen that sufficient space is left between the handle 19 and each of the clamps 75

C for additional frames F to be added should this be required. To prevent lateral movement of the frames F, each of the groups of frames is situated between two annular rings 31 that are longitudinally adjustable on the members 15 or 16.

While the above described device is fully capable of attaining the objects and providing the advantages hereinbefore stated, it is to be understood that it is merely illustrative of the presently preferred form of my invention, and that I do not mean to limit myself to the details of construction herein shown and described other than as defined in the appended claims.

I claim:

1. A card index which includes: a longitudinally adjustable bar, with said bar being formed with a series of grooves that extend the length thereof; a clamp affixed to each end of said bar, with each of said clamps when said bar is properly adjusted being adapted to grip the vertical edges of the sun shield of a vehicle and hold the bar in position thereon; and a plurality of card holding frames, with each of said frames being rotatably mounted on said bar and having a portion thereof adapted to engage said grooves whereby said frame is held in the position in which it is manually placed.

2. A card index which includes: two co-axially positioned members, with each of said members being formed with a series of longitudinally extending grooves in the outer surface thereof, and each of said members on its inner end being provided with a threaded section; a handle situated between the inner ends of said members, with said handle having a longitudinally extending bore that is tapped at each end to engage one of the threaded ends of said members; a pair of clamps, with each of said clamps being affixed to the outer end of one of said members whereby upon said handle being rotated said clamps are moved inwardly to grasp the vertical edge of the sun shield provided in a vehicle and hold said members in a longitudinally extending position thereon; and a plurality of card holding frames, with each of said frames having a portion thereof engaging said grooves whereby said frame is held in the position in which it is manually placed.

3. A card index which includes: two co-axially positioned members, with each of said members being formed with a series of longitudinally extending grooves in the outer surface thereof, and each of said members on its inner end being provided with a threaded section; a handle situated between the inner ends of said bars, with said handle having a longitudinally extending bore that is tapped at each end to engage one of the threaded ends of said members; a pair of clamps, with each of said clamps being affixed to the outer end of one of said members whereby upon said handle being rotated said clamps are moved inwardly to grasp the vertical edge of the sun shield provided in a vehicle and hold said members in a longitudinally extending position thereon; and a plurality of substantially rectangular card holding frames, with each of said frames being mounted on one of said members, and each of said frames having a resilient annular portion that engages said grooves whereby said frame is held in the position in which it is manually placed.

4. A card index which includes: two co-axially positioned members, with each of said members being formed with a series of longitudinally extending grooves in the outer surface thereof, and each of said members on its inner end being provided with a threaded section; a handle situated

between the inner ends of said members, with said handle having a longitudinally extending bore that is tapped at each end to engage one of the threaded ends of said members; a pair of clamps, with each of said clamps being affixed to the outer end of one of said members whereby upon said handle being rotated said clamps are moved inwardly to grasp the vertical edge of the sun shield provided in a vehicle and hold said members in a longitudinally extending position thereon; and a plurality of substantially rectangular frames, with each of said frames having two laterally spaced resilient arms adapted to support a card therebetween, and each of said frames at each end thereof having a resilient ring portion rotatably supporting said frame from one of said members, with a portion of each of said rings being adapted to engage said grooves whereby said frame is held in the position in which it is manually placed.

5. A card index which includes: two co-axially positioned members, with each of said members being formed with a series of longitudinally extending grooves in the outer surface thereof, with each of said members on its inner end being pro-
